(No Model.)

J. M. COOKINGHAM.

NEEDLE CASE.

No. 247,988.

Patented Oct. 4, 1881.

UNITED STATES PATENT OFFICE.

JOHN M. COOKINGHAM, OF HUDSON, NEW YORK.

NEEDLE-CASE.

SPECIFICATION forming part of Letters Patent No. 247,988, dated October 4, 1881.

Application filed June 30, 1881. (No model.)

To all whom it may concern:

Be it known that I, JOHN M. COOKINGHAM, of Hudson, in the State of New York, have invented certain new and useful Improvements in 5 Needle-Cases; and I do hereby declare that the following is a full, clear, and exact description thereof, reference being had to the accompanying drawing, and to the letters of reference marked thereon, which form part of this specification.

The object of this invention is to provide a cheap, light, and durable needle-case having a series of receptacles for holding needles of various sizes, and a cover adapted to be held 15 upon the body of the case by means of springs, and also adapted to be connected therewith in reversed positions, as hereinafter explained, and particularly pointed out in the claims.

In the drawing is represented a perspective 20 view of both the case and lid, the latter with its spring-staples.

A indicates the body of the needle-case, which is preferably composed of some light ornamental wood. It is provided with a series 25 of vertical recesses, a a, which constitute receptacles for needles of various sizes, these recesses being made of such depth that the heads of the needles will project above the upperends of the same, in order that the needles 30 can be readily taken out when desired.

B represents the cover, which is composed of a narrow rectangular wooden strip or bar having a longitudinal channel, b, formed in its under edge, so that when it is applied to 35 the body of the case the heads of the needles will be received in its said channel. In order to hold this cover upon the body of the needle-case, I provide it with the spring-staples C at points upon its under side near the ends, and 40 I form the body of the case with recesses D for receiving the spring-staples. These staples are secured by one end or leg only in the cover,

the remaining ends being shorter, so as not to enter the wood, whereby an effective spring will be produced. I also arrange these spring- 45 staples with the short ends at opposite sides, so as to balance the cover and hold it more securely in place. The cover, when thus made, can have different labels applied to its sides, and can be fitted to the body of the case with 50 either side in front, as desired. The case can also have any desired label or printed directions applied to it.

The cover and body of the case constitute, when fitted together, a flat rectangular block, 55 which will be light and durable, and which will occupy but little space.

It is evident that, if desired, the spring staples can be secured to the body and the recesses made in the cover of the case.

What I claim as my invention, and desire to secure by Letters Patent, is—

1. The needle-case composed of a flat body provided with a series of recesses, constituting compartments for holding needles of various 65 sizes, and a cover having a longitudinal channel for receiving the heads of the needles, and springs for fitting into recesses in the body of the case, substantially as described.

2. The combination, in a needle-case, of the 70 body A, having a series of vertical recesses for receiving the needles, with the cover B, formed with a longitudinal channel along its under side, and the spring-staples C, received in recesses in the body of the case, substantially as 75 specified.

In testimony that I claim the foregoing as my own I affix my signature in presence of two witnesses.

JOHN M. COOKINGHAM.

Witnesses:

WILLIAM V. A. POE,
THEO. M. POE.
